J B Johnson

Wind Wheel

No 20,350.

Patented May 25, 1858.

UNITED STATES PATENT OFFICE.

JAMES B. JOHNSON, OF SAN FRANCISCO, CALIFORNIA.

IMPROVEMENT IN WIND-WHEELS.

Specification forming part of Letters Patent No. 20,350, dated May 25, 1858.

To all whom it may concern:

Be it known that I, JAMES B. JOHNSON, of San Francisco, in the county of San Francisco and State of California, have invented a new and Improved Wind-Wheel; and I do hereby declare that the following is a full, clear, and exact description of the same, reference being had to the annexed drawings, making a part of this specification, in which—

Figure 1 is a front or face view of my improvement. Fig. 2 is a vertical section of the same taken in the line $x x$, Fig. 1. Fig. 3 is a plan or top view of the same.

Similar letters of reference indicate corresponding parts in the several figures.

This invention consists in a peculiar means employed for giving a uniform speed to the wheel during variable degrees of velocity of the wind.

To enable those skilled in the art to fully understand and construct my invention, I will proceed to describe it.

A represents a vertical framing or support, on the top of which a horizontal plate B is attached. This plate B has a vertical annular ledge a near its center, said ledge being concentric with the periphery of the plate B, which is of circular form.

C is a horizontal plate of circular or approximate form having friction-rollers a' attached to its under side, which rollers rest or bear on the plate B. Friction-rollers b are also attached to the under side of the plate C, said rollers being fitted in bent arms, so as to be in a horizontal position and bear against the outer side of the ledge a . The plate B projects a short distance over or beyond the side of the framing A, so that the bent ends of pendants c , which are attached to the plate C, may project underneath the edge of plate B. By this means the plate C is allowed to turn freely on plate B, and at the same time is firmly secured to it and no unnecessary play allowed. (See Fig. 2.)

D is a horizontal shaft, which is fitted in bearings d on the plate C. This shaft has a pinion e placed on it, said pinion gearing into a pinion f on the upper end of a shaft E, which is placed within the framing A, the lower end of shaft E being stepped in the lower end of framing A.

F is a pulley placed on the shaft E, the

power being taken from said pulley. A gear-wheel, however, may be used instead, if desired.

To the front end of the shaft D a wind-wheel G is secured. This wheel is constructed as follows: A hub or boss H is attached to the end of shaft D, and four arms g are attached permanently and radially to said hub or boss. The arms g project from the hub or boss H at equal distances apart, and to each arm g a fan or sail h is attached. These fans or sails may be constructed of wood or metal and of the form shown in Fig. 1, or an approximate form may answer.

Four arms i are fitted in the hub or boss H between the arms g . These arms are not fitted permanently in the hub or boss, their lower ends being allowed to turn in their bearings j . To the arms i fans or sails i' are attached, one to each. The outer ends of the arms i are fitted in rods k , which form a rectangular frame, at the corners or angles of which the outer ends of the arms g are permanently attached, the outer ends of the arms i being allowed to turn freely in the rods k , the arms i of course being considerably shorter than the arms g . The lower end of the arms i are each bent for a short distance at right angles with their main portions, as shown at l , Fig. 2. To the outer end of each part l of the arms i a rod m is attached, and the rods m are connected to a sliding plate or head I placed on the shaft D. The head I has a bent lever J connected with it, the fulcrum of which is at n . The upper end of this lever is connected by a link o with one end of a lever K, which has its fulcrum at p on a bail or curved bar L, attached to the plate C. The opposite end of the lever K is connected with a ball-governor M, which is provided with three balls q q q , the governor being driven by gearing r s , the pinion r being on shaft D and the pinion s on the lower end of the governor-shaft t . (See Fig. 2.)

To the back end of the plate C a geared or toothed segment N is attached. This segment is not in line with the shaft D. It is placed at one side, as shown clearly in Fig. 3.

O is a vane, the rod P of which is pivoted to the plate C at u . This rod has a pinion v attached to its under side, said pinion gearing into the segment N. The axis of the pin-

ion v has a pulley O' attached, and a cord or chain Q passes around said pulley and has a weight S attached to its lower end, the end or chain passing through eyes or guides w .

The operation is as follows: When the wind is moderate, all of the sails $h i'$ are presented to the wind at the proper angle, so as to receive its full effective force; but if the velocity of the wind increases beyond a certain degree the wheel G by its rapid rotation will so influence the governor M that the sails i' will be turned in a reverse direction to the sails h in consequence of said governor acting upon the rods i of the sails i' through the medium of the lever K , bent lever J , and sliding head I , connected with the rods i , as described. This turning of the sails i' in an oblique direction opposite to the sails h of course will retard the speed of the wheel, the sails h being stationary at all times. As the speed of the wheel diminishes, the sails i' are gradually brought back to their original position by the action of the governor, which operates of course in the usual way. By employing the stationary and movable sails, as herein described, the wheel is made to rotate with a steadier motion than when all the sails are made adjustable, as usual, the transitions from fast to slow and vice versa will not be so quick, and the sudden jerks and consequent wear and tear of the working parts of the ordinary wheels and the machinery attached to and driven by them will be avoided.

In order to stop the wheel at any time, the attendant grasps the cord or chain Q and turns thereby the pulley O' , and as said pulley O' turns the pinion v in consequence of gearing into the segment N turns the vane O out of line with the shaft D , as shown in Fig. 3, and as the vane will be turned in line with the wind by the action of the wind against it the wind-wheel will consequently be thrown in an oblique position with the wind and the wheel consequently stopped. This will be clearly understood by referring to Fig. 3, in which the arrow 1 shows the direction of the wind and the relative position of the wheel with it when the wheel is stopped.

I do not claim operating the adjustable sails i' by means of the sliding head or plate I actuated by a governor through the medium of the levers, as shown, for this has been previously used. Nor do I claim the manner of attaching the rotating plate C to the framing A , for this has also been previously done; but,

Having thus described my invention, what I claim as new, and desire to secure by Letters Patent, is—

Constructing the wind-wheel G with stationary and adjustable sails $h i'$, substantially as and for the purpose as herein set forth.

JAMES B. JOHNSON.
